UNITED STATES PATENT OFFICE

WINFIELD SCOTT SMITH, OF OSSINING, NEW YORK

CLOSURE OPERATOR

Application filed November 5, 1930. Serial No. 493,656.

This invention relates to an improved closure operating device, which is especially, but not necessarily, designed for mechanically opening and closing hingedly mounted swingable garage doors.

The invention is primarily designed for home or domestic use, but is susceptible of general application.

The inventive conception relies for novelty upon a structural arrangement which is characterized by inner and outer depressible platforms, actuated by the weight of the automobile, wherein said platforms are so located and arranged as to open and close the doors through the medium of appropriate operating connections.

The specific structural details and the relative arrangement and organization will become more readily apparent from the following description and drawings.

In the drawings:—

Figure 1 is a horizontal sectional plan view showing the general assembly developed in accordance with the present inventive conception.

Fig. 2 is a vertical section observing the structure from the inside of the garage.

Fig. 3 is a longitudinal sectional view.

Fig. 4 is an enlarged detail view showing the operating mechanism between the adjacent cooperating ends of the tiltable platform, the door being swung open.

Fig. 5 is a section on the line 5—5 of Fig. 4.

Fig. 6 is a section showing the cooperating or meeting ends of the depressible platform.

Fig. 7 is a section on the line 7—7 of Fig. 6.

Fig. 8 is a view like Fig. 6, showing the retaining latch and keeper.

In the drawings, the garage is generally designated by the numeral 9, and includes a door frame having vertical end posts 10 with which the doors 11 are hingedly connected as at 12. This is a double door arrangement, and individual means is obviously provided for actuating each door. The means is the same, however, in both instances, and a description of one will suffice for both.

As shown in Fig. 3, there are two platforms, namely an outer platform 13, disposed on the exterior of the garage, and an inner

platform 14. The outer platform is somewhat longer than the inner one and both platforms are normally raised and disposed in spaced relation about the floor or runway 15. If desired a wear plate 16 may be embedded in the runway to accommodate the slidable free end portion of the platform. These platforms are vehicle actuated, that is, they are depressed through the medium of the weight of the vehicle as it moves thereon.

It is obvious that with this arrangement, and through the medium of the operating mechanisms between their respective platforms and door, the doors will be swung to open and closed position as the platforms are depressed, whether the car is entering the garage or leaving the garage.

To hold the doors closed, I provide a keeper plate 17 on the inner platform and cooperating within spring-pressed retaining latch 18 on a suitable carrier bracket, the spring being denoted by the numeral 20. It will be observed that the spaced adjacent end of this platform is provided with angle irons 21 and 22 respectively and these are operatively connected together by suitable connecting pins 23 as represented in Fig. 6.

To understand the operating connection between the platforms and respective doors, I invite attention to Figs. 4 and 5. Here the reference character 24 designates an attaching bracket including a suitable plate 25 secured to the adjacent frame or post 10. This has outstanding webs 26 and is cast as at 27 to provide the reduced extension or journal 28. The numeral 29 designates a hinge mounted on the hinged end of the door. Between this hinge and the bracket is an operating toggle 30 including links 31 and 32. These are pivotally connected together and also pivotally attached to the journal 28 and hinge 29 as shown in Fig. 5.

There is a screw threaded coupling 33 passing pivotally to the link 32. A similar coupling 34 is attached to the platform 14 as shown in Fig. 4 through the medium of an appropriate coupling bracket 35. A rod 36 constitutes the operating connection between these parts 33 and 34 and the toggle.

The numeral 37 designates a coil return

spring secured by a hooked bolt 38 to the web 26 of the attaching bracket. The coiled spring is secured at its lower end to a turn buckle 39, the lower element 40 of which is 5 formed with an eye embracing the aforesaid pin 23 as presented in Fig. 6. Thus there are two individual operating connections, namely the one designated generally by the numeral 41 and the other one by the numeral 42. The 10 operating connection 42 embodies the return spring for closing the doors, and the operating connection 41 the positive thrust rod 36 for opening the doors.

The description, so far as it has gone, shows 15 that the gist of the invention comprehends an arrangement embodying normally elevated inner and outer platforms, 13 and 14, the platform 14 being relatively long and projecting outwardly beyond the hinged garage 20 door, and the platform 14 being somewhat shorter and confined within the interior of the garage.

Assuming that the car is inside of the garage, and it is desired to back out, it is obvious 25 that as the back wheels ride onto the platform 14, both of the platforms are simultaneously depressed. This allows the latch 18 to become released from the keeper 17. It also brings both of the toggle structures 30 into play and serves to thrust both of the garage doors open. As the car moves outwardly beyond the garage doors, and leaves the platform 13, the spring return connections 42 come into play for again lifting or 35 elevating the platform and restoring the mechanical mechanism to its original state, thus closing both of the doors. Hence, it is possible to enter or leave the garage without alighting from the car to manually unlatch 40 and open the doors as is customary.

The gist of the invention, it will be understood, is in the provision of hingedly mounted garage doors, having their lower edges arranged in spaced relation above the meeting ends of the vehicle operated platform, so as 45 to provide for appropriate clearance and as well as systematic and releasing and engaging of the latch 18. Then too, novelty is predicated upon the duplicate arrangement of operating mechanisms or devices at opposite 50 sides of the door frames for producing the desired individual opening and closing of the doors in unison.

The operating connections are each of duplex design, there being an attaching bracket, and a toggle, and a positive or direct operating connection between one of the platforms and one of the links of the toggle. Then too, there is the distinguishable spring embodied 55 operating connection, which constitutes retaining means for closing the doors automatically, at a predetermined time.

The present embodiment of the invention has been disclosed in considerable detail 60 merely for the purpose of exemplification

since in actual practice it attains the features of advantage enumerated as desirable in the statement of the invention and the above description.

It is to be understood that by describing in detail herein any particular form, structure or arrangement, it is not intended to limit the invention beyond the terms of the several claims, or the requirements of the prior art.

Having thus described my invention, what I claim as new is—

1. In a structural assembly of the class described, a door frame, a door hingedly mounted thereon, a bracket connected to one of the side members of the frame, a pair of links pivotally connected together, the outer end of one link being hingedly connected with the door and the outer end of the other link being pivotally connected to the bracket, a pair of retractable platforms located beneath the lower edge of said door and one located within the building and the other exteriorly thereof, pin connections between the adjacent edges of the platforms whereby said platforms are moved in unison, a spring connected with the bracket, means for connecting the other end of the spring to the pin, and a link connection between the inner platform and the inner link of the pair of links.

2. In combination with a building having a door frame and a door for closing the opening formed by said frame, a bracket connected to one side of the frame, a hinge member on the door, toggle links connecting the hinge to the bracket, said links being pivotally connected with the hinge and with the bracket, a pair of platforms one located within the building and the other exterior thereof, means for depressing one of the platforms when the other is depressed, a spring, means for connecting one end of the spring to the bracket, means for connecting the other end of the spring to a platform, and a link connection between the inner platform and one of the links of the toggle links.

In testimony whereof I affix my signature.

WINFIELD SCOTT SMITH.
